COOLING MEANS FOR ROLLS HANDLING
HOT-ROLLED METAL STRIPAlfred E. E. De Witz, Bedford, Ohio, assignor to
The American Steel and Wire Company of New
Jersey, a corporation of New Jersey

Application March 12, 1942, Serial No. 434,402

9 Claims. (Cl. 80—43)

In the hot rolling of steel strip there is frequently employed a unit referred to as a vibrator unit, which is positioned in alignment with the last finishing roll, for receiving the strip from the last finishing roll and retarding the speed of travel of the strip so as to render possible the inspection and gaging of the strip and also to make possible the manual insertion of the first end of the strip for the reeling, or coiling, operation.

Such vibrator unit includes, essentially, two vertically mounted feed rolls, both of which are driven, the axis of one of the rolls being fixed, while the other is adjustable in order to enable the rolls to accommodate various gages of the strip being produced. These vibrator rolls engage the strip on both sides thereof.

Adjacent to the vibrator feed rolls, and receiving the strip therefrom, are two so-called "flipper" rolls which also are mounted vertically, but are not powered to revolve. Mechanical motion is delivered to the flipper unit by suitable crank mechanism operated from a motor and speed reducer separate from the motor which drives the vibrator rolls.

The flipper unit is given a back and forth motion which gives the hot strip a waving motion as it leaves the vibrator and distributes the strip on the run-out table in an edgeways wavy ribbon fashion, such distribution of the strip from side to side on the table making sufficient only a comparatively short run-out table, thus conserving on equipment and mill space.

As the strip at the vibrator unit is at rather high temperatures, say, for example, 1450° F., to 1650° F., and with a lineal speed of the strip at the vibrator unit anywhere from about 583 feet per minute to about 2633 feet per minute, the vibrator rolls become hot, and serious difficulties have been experienced on account of overall heating up of the rolls, bearings, shafts, and gears.

The difficulties arising from such heating have presented no small problems in engineering for obviating these difficulties, and many attempts have been made, but unsuccessfully, to cool the parts affected by the heat. The cooling problem is complicated by the fact that, where high carbon content strip is being produced, any cooling fluid employed for cooling the rolls and associated parts must not come in contact with the hot strip because of the likelihood of the strip being quenched by such contact, and its structure changed thereby with attendant difficulties in the reeling.

Among the attempts that have been made to effect the requisite cooling, there may be mentioned the attempted use of cooling fans, of compressed air, and water applied directly to the rolls. The former attempts succeeded poorly, and the latter attempts were inoperative on account of the above-mentioned quenching effects on the strip.

Operating difficulties and the loss of bearings 10 and gears through such over-heating showed that the problem involved in the successful operation of vibrator units in the production of hot rolled strip is to cool the vibrator at as near the source of heat as possible without interfering with, or changing, the structure of hot rolled strip.

The source of heat referred to above is the hot strip itself, the vibrator rolls contacting therewith, and serving to feed the strip onto the run-out table without, however, reducing, deforming, or otherwise altering the strip.

In view of the failure of the attempts above-mentioned to provide effective cooling, various changes were made in the lubrication system, all 25 of which were ineffectual.

The problem of cooling the vibrator at as near to the source of heat as possible, without interfering with, or changing, the structure of high carbon hot rolled strip, finally was solved through 30 the use of caps on the top of the vertically disposed vibrator rolls into which caps water is allowed to flow at a rate slightly in excess of the rate of evaporation, the flow of water being under close control so as to avoid contact thereof 35 with the strip being rolled.

The invention will be understood more clearly from the accompanying drawings, which show several forms of the invention.

In the drawings:

40 Fig. 1 is a plan view of a vibrator unit embracing the improvements of the present invention, the view including the flipper unit and run-out table, the direction of travel of the hot rolled strip being indicated by the arrow adjacent to 45 the strip;

Fig. 2 is a fragmentary sectional elevation taken on the line II—II of Fig. 1, looking in the direction of the arrows;

Fig. 3 is an enlarged plan view of the improved 50 vibrator unit of the present invention, heavy arrows showing fluid flow;

Fig. 4 is a fragmentary sectional elevation taken on the line IV—IV of Fig. 3, looking in the direction of the arrows;

Fig. 5 is a sectional elevation through the

entire vibrator unit, showing the drive mechanism for the vibrator rolls, as well as further details of the cooling means of the present invention;

Fig. 6 is a sectional plan view on the line VI—VI of Fig. 5, looking in the direction of the arrows;

Fig. 7 is a sectional elevation of a modified form of the invention, the view showing a fragment of a vertically disposed roll with the illustrated form of the invention applied thereto;

Fig. 8 is a plan view of the modification of Fig. 7;

Figs. 9, 10 and 11 are fragmentary sectional elevations of further modified forms of the invention as applied to vertically disposed rolls, and,

Fig. 12 is a sectional elevation of a modified form of the invention as applied to horizontal rolls.

Referring more particularly to the drawings, the vibrator unit is indicated generally at A, it having a roll assembly generally indicated at B, either vertical or horizontal, which is adapted to engage a hot rolled steel strip C, and which is driven by a motor E. A flipper arm F is illustrated generally for pushing the strip C back and forth on a run-out table G.

The vibrator unit A comprises the roll assembly B, which includes two rolls 14, 16 which are generally similar, and which engage the hot strip C sufficiently to feed the strip onto the run-out table G. Both of the rolls are enclosed in a guard 18, which will be referred to further hereinafter, and both rolls are driven positively from a suitable source of power, such as motor E.

Roll 14 is shown as being mounted on a shaft 22, and roll 16 is mounted on a shaft 24. Shaft 22 has a bevel gear 26 keyed thereto, the said gear meshing with a bevel pinion 28 carried on the drive shaft 30, power from the motor 20 thus being transmitted to shaft 22 for causing such shaft to revolve. Shaft 22 carries a gear 32 and shaft 24 carries a gear 34, suitable intermediate driving gears completing the gear train for driving the shaft 24 from the shaft 22 and motor E.

The shafts and power-transmitting means, therefore, are enclosed in a housing 36 having a removable top portion 37 arranged to be dismantled readily by removal of bolts 39 for access into the interior of the housing for servicing the mechanism contained therein. Also, the bottom of the housing is provided with an opening, which is closed normally by a closure 38, for providing access to bearing 40. Also housing 42 for driving shaft bearings 44, 46, may be dismantled readily for permitting access to the bearings. Lubricating means for lubricating the lower portion of shaft 22 and its associated parts may be of any suitable type, such lubricating means being illustrated generally at 48.

As the mechanism is called upon to handle strips of different gages, adjustment of the spacing between rolls 14 and 16 must be provided for such accommodation. For this purpose, it is required that only one of the rolls be adjusted which, in the drawing, is shown to be the roll 16.

For adjustment of this roll, the shaft 24 and roll are arranged to be displacable laterally sufficiently to allow strips of different gages to pass between the rolls, as well as varying gages in one strip. The shaft 24, therefore, is enclosed in a housing 50 which contains the bearings 52 and 54 for the shaft, and adjustment of the shaft is effected by adjustment of springs 56, 58, acting

on the housing 50 through a yoke 60 connected to the housing 50.

Vibratory movement of the unit A is effected through a lever mechanism 62 operated by motor 63.

From the foregoing, it will be seen that the rolls 14 and 16 will become hot through contact with the strip C, heat also being conducted from the rolls through the driving shaft and driving mechanism, with destructive effect, were it not for the interposition of the means of the present invention which are designed to cool the rolls and associated parts of the mechanism.

The cooling means comprise, essentially, cup-like retaining devices positioned on the outer end of each roll, which devices are adapted to hold water which is supplied thereto at a rate slightly in excess of the evaporation rate, so that the outer end of the rolls will be enclosed in a continuously supplied body of water. Since means are provided for withdrawing excess of water, it will be apparent that the outer end of each of the rolls is enclosed in a water jacket through which water is maintained in continuous and vigorous circulation, whereby heat is withdrawn continuously from the rolls, which are kept at temperatures below the boiling temperature of circulating water.

In addition to the mere cooling of the rolls, provision must be made to prevent access of the cooling water to the strip, on account of the fact that any contact of the water with the hot strip causes the strip to be modified unwantedly in its properties.

Various specific means embracing the same inventive thought are illustrated in the drawings. In this connection, reference is made to Fig. 5, which shows the positioning of cap members 64 and 66 on the outer end of the rolls, each of which ends is shown as formed into a channel 65, 67, the walls of which are the hubs 69, 71 of the rolls and an annular flange 68, 70, the cap members 64 and 66 being secured to the flanges 68, 70 by means of bolts 70'. The resulting joints between the cap members and the rolls are made watertight by the provision of seals 72 and 74, the caps 64 and 66 thus defining with the ends of the rolls, a cooling jacket for each roll through which water is kept in continuous circulation, as will be described hereinafter.

Various means for circulating the cooling water are shown in the drawings. In Figs. 3, 4, and 5, water enters through pipes 74, 76 and is withdrawn through pipes 78, 80, these latter being under suction through pumps 75 and 77, which outer pipes are included desirably, although optionally. Each of the pipes 74, 76 is provided with a control valve 82, 84, for controlling the inflow of the water.

As has been pointed out above herein, it is important that contact be avoided between the water and the sheet or strip C. The intake and outlet pipes are positioned in tubular projections 88, 90 of the cap members 64, 66, which projections communicate with the interior of the water jacket for providing means of escape for the steam produced from the water, which water is introduced, as has been pointed out above hereinafter, at a rate slightly in excess of the rate of evaporation. The exhaust pipe in the cooling jacket prevents overflow.

For preventing contact between the water and the sheet or strip C, the rolls are enclosed by guard housings 92, 94, which completely enclose the rolls except for a space directly over the strip

C, which space is covered by a drain 96, the respective channels 98, 100 of which are designed to catch any water sprayed outwardly through the projection 88, 90, as indicated on Fig. 5. This collected water is drained from the channels by pipes 102, 104.

It will be seen, therefore, that efficient cooling means are provided for the rolls, while affording complete protection for the strip.

The guard housings 92, 94 rest on the top portion 37 of the housing 36. The juncture between the housing 36 and its top portion 37 is made tight by a suitable sealing ring 106.

As will be seen from Fig. 5, the flow of water is regulated by the valves 82, 84, so that the quantity of water admitted to the cooling jackets is under continuous control so as to be maintained in proper excess of the rate of evaporation. Naturally, a certain amount of the water retained in the jackets is thrown off tangentially from the top edge of the cap projections 88, 90. The design of each roll guard housing 92, 94 is such that it almost completely encircles its roll.

All of this sprayed water, with the exception of that thrown off in the small angle above the drain 96, lies inside of the roll guards 92, 94 runs down inside the guards, drops on the housing top 37 and drains off without interference with the strip C. The slight amount thrown off above the spray-catcher 96 is caught thereby, and is drained away through the pipes 102, 104.

While from the foregoing, it will be seen that the outlet pipes 78 and 80 and the pumps 75 and 77 may be eliminated, and the entire excess water allowed to spray out as described above, in practice it is found to be desirable to provide such pipes for effecting closer control or balance of the water supply in the cooling jacket, particularly at roll speeds that are insufficient to spray out the water as described above.

With the employment of the outlet pipes 78 and 80, it may be unnecessary to provide a spray-catcher, as it is possible to control water intake and outflow so that no water at all is sprayed out of the jacket. But in practice, as a complete safeguard, it is desirable to utilize the spray-catcher 96.

When the spray-catcher is used, it is desirable to make it a component part of the roll guards 92, 94, the resulting assembly becoming thereby a unitary structure.

Fig. 7 shows a construction similar to that of Figs. 1 to 6, inclusive, except that the straight-ended outlet pipe of Fig. 5 is replaced by an outlet pipe having a curved end, which is designed to reduce further any amount of water sprayed from the cooling jacket. In Fig. 7, the roll 166, which is entirely similar to the rolls 14, 16 is mounted on a shaft 107 enclosed in a housing 109, and is provided with a water cap 108, similar to the caps 64, 66. The water intake pipe is indicated at 110, and is controlled by a valve 112. The drain pipe is indicated at 114, which, in the present modification, has a curved end 116 which is placed so that its opening 118 is disposed oppositely to the direction of rotation of the roll. The motion of rotation of the roll produces a pumping action which forces the water from the jacket, although, of course, the action may be augmented by the use of a suction pump, if such is found to be desirable. Since the end 118 of the pipe 116 can be brought closer to the peripheral wall of the water jacket, it acts effectively to pick up water thrown to the periphery by centrifugal force of rotation.

Fig. 9 shows a modification wherein drainage is effected through holes in the end web of the roll. In this view, the roll 120 is mounted on shaft 122 in housing 124 and is provided with a water cap 126, similarly as described above. Intake pipe 128, provided with control valve 130, supplies water to the interior of the cooling jacket.

The end web 132 of the roll 120 is provided with holes 134. The water flows in from pipe 128 in controlled flow, and fills the jacket, draining out through holes 134 in the web 132, to the top of the vibrator housing, represented at 136 in Fig. 7, flowing from there to a drain not shown, contact between the water and strip thereby being avoided.

In Fig. 10 the roll itself is modified for internal cooling. The roll is indicated at 138, which is mounted on shaft 140 in housing 142, this construction being the same as in preceding views. Water is supplied to the jacket 144 from a pipe 146 provided with a valve 148. The interior of the roll, which is hollow, is divided by a top web 150 and a bottom web 152, which define between them a cooling chamber 154. Holes 156 pass through the top web and holes 158 pass through the bottom web, through which holes water passes, the flow being controlled so that the chamber 154 is filled. The water flows out from the roll through bottom holes 158, and over the top 160 of the vibrator housing, as has been described above, without contacting with the strip.

Fig. 11 shows a further modification wherein the roll 162 has an open end and a water spray 164 is inserted within the roll to cool it through the cooling effects of jets of water sprayed into the roll. The excess water drains over the vibrator housing, as has been described above, and it does not contact with the rolled strip.

Fig. 12 shows a modification as applied to horizontal rolls. The rolls are indicated at 166, 168; water caps 170, 172 are applied thereto through which enter the water supply pipe 174 and drain pipe 176. The supply pipe 174 has a curved end 178 for supplying water to the outer wall of the water jacket and pipe 176 is curved as indicated at 180 to withdraw water from the cylindrical layer 182 thereof, which is formed by centrifugal force incident to operative rotation of the rolls. Pipe 176 acts as a siphon to remove excess water from the cooling jacket, a suction pump 184 being inserted in the pipe 176 if desired.

In all of the illustrated forms, it will be seen that as the rolls turn, the speed of rotation forces the water into the shape of a cylinder which is held by the outer wall of the cooling chamber and adjacent to the zones of maximum heating of the roll. Also, the outlets are positioned so that the heated water is withdrawn continuously as it becomes hot, and immediately and continuously becomes replaced by fresh cold water. Therefore, there is maintained the maximum cooling effects at the outer portions of the roll, which portions become heated the greatest, and consequently the paths of heat flow are mainly through these outer portions of the roll, so that destructive heat is prevented from passing into the body of the rolls to the driving shaft upon which the roll is mounted, thereby giving the maximum cooling effects.

I claim:

1. Apparatus for feeding hot rolled steel strip onto a run-out table, which comprises the combination with a pair of feed rolls adapted to engage a hot strip and to become heated thereby,

of cooling means for the rolls comprising a cap mounted on the end of the roll defining with the roll a chamber adapted to contain water in heat exchange relation with the roll, means for introducing water into the chamber, means for controlling admission of water to the chamber for introducing the water into the chamber at a rate somewhat in excess of the rate of evaporation, outlet means for the water, causing the said water to be constantly withdrawn, whereby a substantially constant amount of water is retained in the cooling chamber, the said chamber having an outer wall adapted to retain a cooling cylinder of the water produced by centrifugal force of rotation of the roll, the said cylinder being located adjacent to the areas of maximum heating of the roll, and in heat exchanging relation thereto, whereby excessive heat is prevented from passing into the body of the roll, and means for preventing heated water being withdrawn from contacting with the hot strip being handled by the rolls, the said outlet means being positioned to continuously withdraw water from zones of maximum heat, thereby enabling continuous replenishment thereof with fresh cold water.

2. Apparatus for feeding hot rolled steel strip onto a run-out table, which comprises the combination with vertically disposed feed rolls adapted to engage both sides of a hot strip and to become heated thereby, each of the said rolls presenting a top end, cooling means on the top ends of the rolls coextensive therewith, the cooling means including a cap mounted on each of the rolls, each cap defining with its roll a chamber adapted to contain water in heat exchange relation with the roll, means for continuously introducing water into the chamber, means for controlling admission of water to the chamber at a rate somewhat in excess of the rate of evaporation of the water, outlet means for the water causing the said water to be constantly withdrawn, thereby preventing overflowing of the chamber and assuring continuous circulation of fresh cold water in the chamber, the said chamber including an outer wall adapted to retain a continuously renewed cylinder of cooling water produced and maintained by centrifugal force of rotation of the roll, the said cylinder being located adjacent to the areas of maximum heating of the rolls and in heat exchanging relation thereto, whereby excessive heat is prevented from entering substantially into the body of the roll, and means for preventing heated water being withdrawn from contacting with the hot strip being handled by the rolls.

3. Apparatus for feeding hot rolled steel strip onto a run-out table, which comprises the combination with vertically disposed feed rolls adapted to engage both sides of a hot strip and to become heated thereby, each of the said rolls presenting a top end, cooling means on the top ends of the rolls coextensive therewith, the cooling means including a cap mounted on each of the rolls, each cap defining with its roll a chamber adapted to contain water in heat exchange relation with the roll, means for continuously introducing water into the chamber, means for controlling admission of water to the chamber at a rate somewhat in excess of the rate of evaporation of the water, and outlet means for the water causing the said water to be constantly withdrawn, thereby preventing overflowing of the chamber and assuring continuous circulation of fresh cold water in the chamber, the said chamber including an outer wall adapted to retain a

continuously renewed cylinder of cooling water produced and maintained by centrifugal force of rotation of the roll, the said cylinder being located adjacent to the areas of maximum heating of the rolls and in heat exchanging relation thereto, whereby excessive heat is prevented from entering substantially into the body of the roll.

4. Apparatus for feeding hot rolled steel strip onto a run-out table, which comprises the combination with vertically disposed feed rolls adapted to engage both sides of a hot strip and to become heated thereby, each of the said rolls presenting a top end including a web, of cooling means on the top ends of the rolls coextensive therewith, the cooling means including a cap mounted on each of the rolls, each cap defining with its roll a chamber adapted to contain water in heat exchange relation with the roll, means for continuously introducing water into the chamber, means for controlling admission of water to the chamber at a rate somewhat in excess of the rate of evaporation of the water, and outlet ports extending through the web for draining water from the chamber, thereby causing the water to be constantly withdrawn, thereby preventing overflowing of the chamber and assuring continuous circulation of fresh cold water in the chamber, the said chamber including an outer wall adapted to retain a continuously renewed cylinder of cooling water produced and maintained by centrifugal force of rotation of the roll, the said cylinder being located adjacent to the areas of maximum heating of the roll and in heat exchanging relation thereto, whereby excessive heat is prevented from entering substantially into the body of the roll.

5. Apparatus for feeding hot rolled steel strip onto a run-out table, which comprises the combination with vertically disposed feed rolls adapted to engage both sides of a hot strip and to become heated thereby, each of the said rolls presenting a top end, cooling means on the top ends of the rolls coextensive therewith, the cooling means including a cap mounted on each of the rolls, each cap defining with its roll a chamber adapted to contain water in heat exchange relation with the roll, means for continuously introducing water into the chamber, means for controlling admission of water to the chamber at a rate somewhat in excess of the rate of evaporation of the water, and an outlet pipe extending into the chamber and having its open end disposed in opposition to the direction of rotation of the rolls, thereby causing water from the chamber to be withdrawn constantly from the chamber, thereby preventing overflowing of the chamber and assuring continuous circulation of fresh cold water in the chamber, the chamber including an outer wall adapted to retain a continuously renewed cylinder of cooling water produced and maintained by centrifugal force of rotation of the roll, the said cylinder being located adjacent to the areas of maximum heating of the roll and in heat exchanging relation thereto, whereby excessive heat is prevented from entering substantially into the body of the roll.

6. Apparatus for feeding hot rolled steel strip onto a run-out table, which comprises the combination with feed rolls adapted to engage both sides of a hot strip and to become heated thereby, cooling means for the rolls comprising a cap mounted on an end of each roll defining with the roll a chamber adapted to contain water in heat exchange relation with the roll, means for introducing water into the chamber, means for con-

trolling admission of water to the chamber for introducing the water into the chamber at a rate somewhat in excess of the rate of evaporation, outlet means for the water causing the said water to be constantly withdrawn, whereby an effective amount of water is retained in the cooling chamber while avoiding overflowing of the chamber, the said chamber having an outer wall adapted to retain a cooling cylinder of the water produced by centrifugal force of rotation of the roll, the said cylinder being located adjacent to the areas of maximum heating of the rolls and in heat exchanging relation thereto, whereby excessive heat is prevented from passing into the body of the roll, guard means for the rolls substantially enclosing the rolls, and means mounted on the guards for receiving and retaining spray ejected from the said chambers during rotation of the rolls and projected beyond the limits of the roll guards, thereby preventing contact of water with the hot strip being handled by the rolls.

7. Apparatus for feeding hot rolled steel strip onto a run-out table, which comprises the combination with vertically disposed feed rolls adapted to engage both sides of a hot strip and to become heated thereby, each of the said rolls presenting a top end, of cooling means on the top ends of the rolls coextensive therewith, the cooling means including a cap mounted on each of the rolls, each cap defining with its roll a chamber adapted to contain water in heat exchanging relation with its roll, means for continuously introducing water into the chamber, means for controlling admission of water to the chamber at a rate somewhat in excess of the rate of evaporation of the water, and outlet means in the roll for the water causing the said water to drain through the interior of the roll, thereby preventing contact of water with the hot strip being handled by the rolls and preventing overflowing of the chamber while assuring continuous circulation of fresh cold water in the chamber, the said chamber including an outer wall adapted to retain a continuously renewed cylinder of the water produced and maintained by centrifugal force of rotation of the roll, the said cylinder being located ad-

jacent to the areas of maximum heating of the roll and in heat exchanging relation thereto, whereby excessive heat is prevented from entering substantially into the body of the roll.

8. Apparatus for feeding hot rolled steel strip onto a run-out table, which comprises the combination with horizontally disposed feed rolls adapted to both sides of a hot strip and to become heated thereby, each of the said rolls presenting and outer end, cooling means on the outer ends of the rolls coextensive therewith, the cooling means including a cap mounted on each of the rolls, each cap defining with its roll a chamber adapted to contain water in heat exchange relation with the roll, means for continuously introducing water into the chamber, means for controlling admission of water to the chamber at a rate somewhat in excess of the rate of evaporation of the water, and syphonic outlet means for the water causing water to be withdrawn continuously from the chamber, thereby preventing overflowing of the chamber and assuring continuous circulation of fresh cold water in the chamber, the said chamber including an outer wall adapted to retain a continuously renewed cylinder of cooling water produced and maintained by centrifugal force of rotation of the roll, the said cylinder being located adjacent to the areas of maximum heating of the rolls and in heat exchanging relation thereto, whereby excessive heat is prevented from entering substantially into the body of the roll.

9. Apparatus for feeding hot rolled steel strip onto a run-out table, which comprises the combination with feed rolls adapted to engage both sides of a hot strip and to become heated thereby, each of the said rolls being hollow, and cooling spray means positioned interiorly of the rolls adapted to spray cooling fluid against the rolls, the said rolls having an open end and having a portion defining a protective apron enclosing the spray means and preventing engagement of the spray fluid with the hot strip being handled by the rolls.

ALFRED E. E. DE WITZ.
